United States Patent Office.

LUCIUS C. CHASE, OF BOSTON, MASSACHUSETTS.

Letters Patent No. 69,768, dated October 15, 1867.

IMPROVED BLANKET-FASTENER.

The Schedule referred to in these Letters Patent and making part of the same.

TO ALL WHOM IT MAY CONCERN:

Be it known that I, LUCIUS C. CHASE, of Boston, in the county of Suffolk, and State of Massachusetts, have invented a new and useful Improved Fastener for Horse-Blankets; and I do hereby declare that the following is a full, clear, and exact description of the construction and operation of the same, reference being had to the accompanying drawing, forming a part of this specification, in which—

Figure 1 is a plan, and

Figure 2 a longitudinal section of the device as applied.

This improvement relates to a new method of fastening a horse-blanket across the chest of a horse, and consists, first, in a peculiar metallic stud, fastened by rivets to the blanket; and, second, in looping together the two sides of the blanket by means of this stud and a slotted leather thong, also riveted in a peculiar way to the blanket, the whole making a device cheaper, easier to operate than, and equally effective with, buckle or buttons.

In the drawings, A is a blanket, to be fastened together across a horse's breast, for instance. Upon the two parts which are to be brought together by the fastening we attach at *a a'* a shield of leather. I then take a metallic casting, of the plan shown in fig. 1, *b c d*, and of the section shown in fig. 2, *b c d*, consisting of plate *b*, stud *c*, and loop *d*, and attach the same on the opposite side of the blanket from shield *a* by means of rivets *e* and *f*, passing through shield, blanket, and plate, and then upset. The stud *c* is of an elliptical shape, and is arranged so that its longest diameter shall be in the direction of the strain to be brought to bear upon it. The loop *d* may be omitted, but I prefer to make it as shown, continuous with the plate *b*, inclined at a small angle with said plate, and forming a sort of standing loop for the strap. To make the other end of the fastening, I take a strap of leather, *g*, make a slot, *h*, in it, and fasten it to the blanket over shield *a'* by rivets *e' f'*, passing through shield, blanket, and strap, and twin washer *j*, of the plan shown in fig. 1, and then upset. The strap is fastened to the stud as shown in section, fig. 2, by slipping the slot *h* over stud *c*, and tucking strap *g* through loop *d*.

I claim as my invention, and desire to secure by Letters Patent—

1. The arrangement of stud *c* and plate *b* in connection with each other, and also with loop *d*, when fastened to a blanket by means of shield *a* and rivets *e f*, substantially as and for the purpose described.
2. And in combination therewith, the strap *g*, slotted at *h*, when fastened to the blanket between shield *a'* and twin washer *j* by rivets *e' f'*, as and for the purposes described.

LUCIUS C. CHASE.
